UNITED STATES PATENT OFFICE.

OLIVER B. WOODROW, OF NEWTON, IOWA.

WASHING MACHINE.

Application filed April 13, 1925. Serial No. 22,796.

The object of my invention is to provide a washing machine of the type intended for domestic use for cleaning clothes, and of simple, durable and inexpensive construction and designed to clean clothes in a convenient, facile and economical manner.

My invention is especially designed to be used in connection with metal (usually copper) tubs that are operated on the principle known as the vertical oscillator type, and one of the objects of my invention is to provide agitator blades on the interior of the tub so constructed, arranged and combined with the thin metal tub as to strongly and firmly brace the tub.

My invention consists in the construction, arrangement and combination of the various parts of the device, whereby the objects contemplated are attained, as hereinafter more fully set forth, pointed out in my claim, and illustrated in the accompanying drawings, in which:

Figure 1 shows a top or plan view of a washing machine body with the cover removed, and illustrating my invention, the arrows therein illustrating the direction of movement imparted to the water and clothes when the machine is in operation.

Figure 2 shows a vertical central sectional view of a washing machine embodying my invention, the arrows indicating the direction of movement imparted to the water and clothes during one movement of the washing machine; and

Figure 3 shows an enlarged detail sectional view on the line 3-3 of Figure 2.

Referring to the accompanying drawings, I have used the reference numeral 10 to indicate generally the washing machine body which is preferably cylindrical in shape of a flat bottom and open at its top. The body is preferably made of thin sheet metal such for instance as copper, which is usually tinned on the interior.

On the interior of the body I have provided a series of three agitator blades, each of which is preferably composed of a body portion preferably of cast metal. The outer edge of this agitator blade is shaped to fit against the adjacent side of the washing machine body and to extend upwardly to a point adjacent to the normal water level within the body. The bottom edge is shaped to lie flat against the bottom of the tub and to extend approximately two-thirds of the

distance from the periphery of the body to the center thereof. The sides of the agitator blade are flat.

The top of the agitator blade is extended first inwardly toward the center of the tub 60 then is curved downwardly and inwardly at 15, then straight downwardly at 16, then curved downwardly and toward the center of the tub at 17, then substantially horizontally inwardly toward the center of the 65 tub at 18 and is then curved downwardly and toward a vertical position at 19.

For securing the agitator blade to the tub I provide on the sides of each blade near the top and near the bottom on the vertical 70 side and near the inner end of the substantially horizontal side an outwardly extended lug 20, and rivets 21 are extended through said lugs and through the adjacent portions of the sheet metal body, thus firmly holding 75 the sides and bottom of the body to the agitator blades, and bracing the body rigidly against the strains to which they are ordinarily subjected. The body is further braced by means of a series of reinforcing ribs 21^a 80 formed in the metal of which the body is composed, one series being extended through the body circumferentially at a point about midway between the top and bottom of the body, another series near the bottom and a 85 third series in the bottom itself about midway between its center and circumferentially. This construction of the blade does not in any way interfere with the use of the reinforcing ribs in the body or bottom of the 90 body, and the blades and ribs coact in strengthening and bracing the entire body portion.

I am aware that heretofore domestic washing machines have been operated by imparting to the washing machine body an alternating rotary motion in a horizontal direction, and I am also aware that machines of this class have been provided with agitator ribs secured to the bottom thereof and extended upwardly a short distance, and also in other instances that machines of this character have been provided with radially extended ribs secured to the inner surface of the body projected a short distance inwardly. I have carefully observed and noted the tubs both as to the production of suds and the time required for a thorough cleansing of clothes, and I have also experimented extensively and carefully observed and noted 100 105 110

the result both as to the production of suds and the time required for cleaning the clothes with my improved washing machine, and have proven that the results obtained by the use of my machine are greatly superior to the results obtained by the use of the alternating rotary washing machines now in common use, and that said improved results are due to what, at first glance, 10 might seem to be mere changes in relative size and proportion of the parts, but which I have demonstrated to be produced as a result of a new construction and combination of parts which produces a new principle of 15 operation.

My invention lies in the shape or configuration and the relative arrangement of the three agitator blades within the body, and by reason of these things I am enabled 20 to produce the improved result which I have attempted to illustrate by arrows in the drawings.

Assuming that the body is filled with water, soap and clothes to the level indicated in Figure 2, and that the body has an alternating rotary motion through a segment of a circle applied to it, and assuming further that, as illustrated in Figure 2, the face of the blade shown at the left of said 30 figure is moving forwardly, then that part of the contents of the body that is in contact with the lower portion of the agitator blade will be forced upwardly, as indicated by the dotted lines at 22, and that portion 35 of the contents of the body that is being engaged by the upper portion of the blade will be forced straight inwardly toward the center of the body, as indicated by the dotted line at 23. These two currents are obviously 40 thrown in converging directions, and that portion of the contents that are engaged by the central portion of the blade are forced both upwardly and inwardly toward the center of the tub, as indicated by the dotted 45 lines at 24. When these three currents unite they will assume substantially parallel lines of travel, as shown at 25, and the ultimate result is that a relatively strong current is produced which flows upwardly through the 50 body, and in a direction approaching the center of the tub, and this current under the normal motion applied to the tub is so strong as to lie slightly above the level of the surface of the water in the tub, as shown by 55 the arrows in Figure 2. During this movement of the tub the action of the water on the opposite side of the same blade is substantially as follows:

As the blade advances, and its advance 60 side forces the water in the direction before indicated, its following side will tend to create a vacuum and hence water will be drawn from all of the surrounding parts of the body into the portion immediately in the 65 rear of the blade, and this will tend to form

a whirling movement, which I have illustrated by dotted lines 26 in Figure 1.

Furthermore, the current that forms this whirl pool will tend to move downwardly toward the bottom of the tub, due to the fact 70 that the currents produced by the front edge of the adjacent blade will act in such a manner as to produce this downward movement.

In Figure 1 I have illustrated by the arrows 27 the general line of movement of the currents 25, as viewed from the top. Obviously when the movement of the body is reversed in completion of a segment of a circle, the relative movement of the currents 75 of water is correspondingly reversed.

It is well known that the best results are attained in washing machines when they operate to present each portion of every article within the washing machine body as frequently as possible to the action of the 80 water and soap. In my improvement this advantageous result is attained to a maximum degree, because during each operation of the washing machine body, one part of a garment is caught by the current indicated 85 in Figure 2 by the numerals 22, 23, 24 and 25, and the part thus engaged is forced rapidly upwardly and toward the center of the washing machine body, whereas the other part of the same garment on the opposite side 90 of the agitator blade is caught by the current illustrated in Figure 2 by the numeral 26, and is drawn downwardly and in an opposite direction into the whirl pool being 95 formed on the opposite side of the agitator 100 blade, so that the movement of each garment is not only in a direction tending to stretch out the garment instead of massing 105 it together with one part moving toward the top of the body and another part moving toward the bottom, and in addition to this stretching out and untangling action applied to the clothes, the currents are so concentrated at the point where the currents, 110 indicated by the numerals 22, 23 and 24, converge that a strong flow at that point is produced, giving a rapid cleansing movement to a garment which is thus stretched out between the opposing currents operated 115 on opposite ends of the same garment.

It is important that the space between the inner ends of the agitators be left open and unobstructed so that garments may move readily from one compartment in the interior of the body across the center to another compartment, as any obstruction located in this place would prevent such movement of the clothes and cause them to become caught, tangled and massed at some point.

In practice I have found that with my improved machine, an unusually large quantity of suds is produced very rapidly, and in addition to this I have found that a thorough cleansing of garments within the tub is effected in a minimum of time, and that there 125

are no such strains applied to any of the garments that would tend to tear the most delicate fabrics.

I claim as my invention:

- 5 In a washing machine, the combination of a tub body having a bottom and sides, a series of agitator blades mounted therein, each blade being formed with an upright member with its outer edge adjacent to the side of the tub body and its inner edge projected toward the center of the tub body, each blade being also formed with a lower portion adjacent to the bottom of the tub body and extended upwardly a short distance from the tub body, the inner end of said lower portion being spaced apart a considerable distance from the center of the tub body, and the inner edge of the upright mem-

ber of the blade being spaced substantially midway between the inner edge of the lower portion and the outer edge of the tub body, the space within the interior of the body between the inner ends of the blades at the bottom being free and unobstructed to permit the passage of garments across the center of the body by the currents created by the agitator blades when the body is oscillated, the upwardly extended portion being designed to create currents of water within the tub in a direction toward the center of the tub and the lower portion of the blade being designed to create upwardly extending currents within the body of the tub, substantially as and for the purposes stated.

OLIVER B. WOODROW.
